CRYOSURGICAL INSTRUMENT

Michael D. Bryne, Vernon, Conn., assignor to
Brymill Corp., Vernon, Conn.

Filed Oct. 19, 1970, Ser. No. 25,553

Term of patent 14 years

Int. Cl. D24—02

U.S. Cl. D83—12

FIG. 2

FIG. 1 is a perspective of the cryosurgical instrument;
FIG. 2 is a rear elevation view of the cryosurgical instrument;
and

FIG. 3 is a bottom plan view of the cryosurgical instrument.

I claim:

The ornamental design for a cryosurgical instrument,
substantially as shown.
